UNITED STATES PATENT OFFICE.

WILLIAM LEFÉVRE CRANSTONE, OF MELBOURNE, VICTORIA.

COMBINATION PENCIL POINT-PROTECTOR AND SHARPENER.

SPECIFICATION forming part of Letters Patent No. 661,955, dated November 20, 1900.

Application filed July 9, 1900. Serial No. 22,937. (No model.)

To all whom it may concern:

Be it known that I, WILLIAM LEFÉVRE CRANSTONE, medical practitioner, a subject of the Queen of Great Britain and Ireland, residing at 11 Victoria street, Melbourne, in the county of Bourke, Colony of Victoria, have invented certain new and useful Improvements in Combination Pocket Pencil Point-Protectors and Sharpeners, of which

10 the following is a specification.

The object of my invention is to provide a combination pocket point-protector and sharpener for pencils which shall not only be cheap in first cost, durable, and light and 15 convenient for the pocket, but which shall also be instantly usable either as a point-protector or as a sharpener.

My invention consists in the combined combination pencil point-protector and sharpener 20 and in the combination and arrangement of its various parts, substantially as will be hereinafter pointed out, and finally embodied in the claim.

My invention is fully illustrated in the accompanying drawings, wherein—

25 Figure 1 is a perspective view, partly in section, of my invention shown as attached to a pencil; and Fig. 2 is a view in side elevation, partly in section, of a slight modification of the invention.

30 In the accompanying drawings, *a* designates a light frame which is provided with openings *b* and *c* at its respective ends, the former being adapted to receive the body of the pencil, while the latter is provided for the admission of the pencil-point. Said frame carries a cutter *d*, which is arranged therein and secured thereto in the usual manner, and *e* designates a milled knob forming an integral projection of the frame, said knob being 35 penetrated by the opening *c*. The sectional contour of the frame *a* is preferably circular.

40 *f* designates a tubular holder, which consists of sheet metal and which comprises a tubular casing *g*, adapted for the reception of the frame *a*, and a slotted sleeve portion *h*, having a smaller diameter than said casing.

i designates a slit in the sleeve portion *h*.

45 The length of the casing *g* is greater than 50 that of the frame *a*—that is to say, the length of said frame as measured from the annular

shoulder *j* to the shoulder *k* thereof. The frame therefore has longitudinal as well as rotary movement in the casing, its longitudinal movement being, however, limited by the 55 abutment *l*, formed between the casing and the sleeve portion, and another abutment *m*, formed by turning in the edge at the free end of the casing.

In the modification shown in Fig. 2 the 60 frame *a'*, having the milled knob *e* and the cutter *d*, as in the case of the device already described, is of conical form. The end of the frame away from the milled knob consists of a tubular extension *n*, having its extremity 65 of reduced diameter and turned inwardly, the internal tubular portion *o* of said extension thus formed by turning in the extremity of the extension being flared at its end, so as to form an annular recess *p*. The internal 70 tubular portion *o* of the extension *n* receives a sleeve *q*, which loosely fits therein and which is provided with a slit *r*, which permits expansibility in said sleeve, which is thus adapted to snugly fit the body of the pencil, as in 75 the case of the sleeve portion *h*. In order to prevent the separation of the sleeve from the frame, in which said sleeve has longitudinal movement, its upper end is provided with an external bead *s*, approximately fitting the recess *p*.

80 It will be observed that in either of the forms of my invention one of the two independently-movable members of the device receives the other and has an annular recess, 85 as *x*, Fig. 1, or *p*, Fig. 2, in which a shoulder, as *k*, Fig. 1, or *s*, Fig. 2, on said other member is movable. Thus the member which clasps the pencil and which is arranged so as to be conveniently grasped by the hand of 90 the operator may be drawn upon, so as to force the cutter-carrying member snugly against the pencil in such manner that no looseness of parts can accrue, as when the device is out of use and serving as the point- 95 protector.

Having thus fully described my invention, what I claim, and desire to secure by Letters Patent, is—

100 In a combined pencil sharpener and point-protector, the combination of two substantially tubular members projecting the one

into the other, one of said members having an annular internal recess and the other having an abutment projecting into said recess, and one of said members being the cutter-
5 carrying member and the other being expandable and adapted to clasp the pencil, substantially as described.

In witness whereof I have hereunto set my hand to this specification in the presence of two witnesses.

WILLIAM LEFÉVRE CRANSTONE.
